His Attorney.

UNITED STATES PATENT OFFICE

CLIVER C. TRAVER, OF SCHENECTADY, NEW YORK, ASSIGNOR TO GENERAL ELECTRIC COMPANY, A CORPORATION OF NEW YORK

CIRCUIT INTERRUPTER

Application filed July 12, 1926. Serial No. 121,894.

The invention relates to circuit interrupters, particularly those having magnetic blowouts for extinguishing the arc produced upon interruption of the circuit and the principal object of the invention is to provide an improved form of magnetic arc blowout arrangement suitable for high voltage heavy duty service.

Due to the relatively great length to which a high voltage power arc must be drawn before it is extinguished, together with the relatively large amount of energy released in the arc, the usual form of magnetic blowout for quenching and dissipating the arc between switch contacts, as commonly employed in low voltage service, is incapable of satisfactorily attenuating and extinguishing such arcs as are encountered, for example, in high voltage transmission line service. However, with my improved form of magnetic blowout, the arc is received from the switch contacts and preferably both ends of the arc are rapidly moved so as to stretch the arc to a relatively great length. At the same time a progressively increasing impedance is inserted in the arc circuit so as to reduce the current and consequently the energy in the arc. Thus as the length of the arc is rapidly increased and the energy in the arc is rapidly decreased my improved blowout enables even high voltage, power arcs to be quickly dissipated. Furthermore, my improved magnetic arc blowout is of such simplified and rugged construction as to successfully withstand severe arcing service.

In carrying the present invention into effect in a preferred form, the circuit interrupter is provided with a magnetic blowout in the form of an elongated winding for receiving the arc from a suitable switch. The successive turns of the winding are spaced apart and disposed so as to supply a magnetic flux transverse to the path of the arc. Preferably the magnetic arc blowout winding is formed upon a core of arc-resisting material with the successive turns of the winding skewed or disposed at an acute angle with the axis of the winding so as to give a large component of leakage flux between the successive turns of the winding

which is transverse the axis of the winding. Thus, with the winding electrically connected to one of the switch members and arranged to receive the arc therefrom so as to energize a portion of the turns of the winding by the current flowing in the arc, the end of the arc is rapidly driven along the successive turns of the winding by the transverse flux component. As the end of the arc travels along the successive turns of the winding the arc is drawn out and attenuated and, at the same time, the inclusion of the additional turns of the winding in the arc circuit serves to insert an increasing reactance therein until the arc is finally dissipated.

A more complete understanding of the invention may be had from the accompanying drawing which illustrates a high voltage power circuit interrupter embodying a preferred form of the invention. In the drawing Fig. 1 is an elevation of a circuit interrupter showing a preferred arrangement of my improved form of magnetic arc blowout; Fig. 2 is a top view of the magnetic arc blowout showing the arrangement of the blowout winding more in detail; and Fig. 3 is a cross-sectional view of the blowout more fully showing the construction thereof.

The circuit interrupter shown in Fig. 1 comprises the switch 10 and the cooperating magnetic arc blowouts 11 and 12 for receiving and dissipating the arc resulting upon operation of switch 10 to open the circuit of the high voltage power conductors L1, L2. The switch 10 is shown as of the auxiliary break type having a main switch contact 13 operable into and out of engagement with the stationary contact 14 and the auxiliary or arcing switch 15 cooperating with the arcing contact 16. The arcing contact 16 is in the form of a shell or enclosure about the blowout coil 17, which is connected at one end to the arcing terminal 16 and at the other end to the main switch contact 14.

The magnetic arc blowouts 11 and 12 each comprise, in accordance with my invention, a conductor in the form of an elongated winding with the successive turns of the winding spaced apart and disposed to supply a magnetic flux transverse the path of the

arc received from switch 10. As more clearly shown in Fig. 2, the blowout 12 is formed of a conductor 18 which is wound about a core of insulating material 19, such as asbestos board or the like, having a series of notches 20 cut in the opposite sides thereof as illustrated, or provided with other suitable means for rigidly holding the successive turns of the conductor in fixed spaced relation. 10 The core 19 may be of rectangular cross-section as shown so that the successive turns of the conductor 18 also are substantially rectangular, or the core and turns may be of circular section if desired. In either case, 15 preferably suitable notches 20 are so arranged and the conductor 18 is so wound that the successive turns of the conductor are skewed or disposed at an acute angle to the axis of the winding. In this way each of the successive turns of the winding 18 is capable of 20 setting up a flux transverse to the axis of the winding. Preferably the successive turns of the winding overlap so that the transverse leakage flux component at any point is of 25 increased value. The turns of the winding 18 may be retained in the notches of the core 19 by means of the side boards 21 and 22, also of suitable insulating material such as asbestos board, which extend slightly above 30 the top of the core 19 as shown more in detail in Fig. 3. With this construction the exposed portions of the overlapping turns of winding 18 serve as a composite arcing terminal for receiving the arc from the switch 35 10 and the transverse component of flux set up upon flow of the current in the arc through the successive turns of winding 18 serves to rapidly move the end of the arc along the winding. It will be observed that the windings of the magnetic arc blowouts 11 and 12 40 are skewed in opposite directions in order that each may set up a transverse magnetic flux in the proper direction to cause movement of the ends of the arc upwardly along 45 the top of the blowouts. The conductor 18 thus forms a plurality of blowout coils, each of which has arcing terminals, the terminals being arranged along a given path so as to be successively included in circuit with the 50 arc stream.

The operation of the interrupter shown is as follows: When the switch 10 is opened the main contact 13 first disengages the co-operating contact 14 thereby causing all of 55 the current flowing in the supply lines L1, L2, to pass through the blowout coil 17 and the auxiliary arcing switch 15. As the latter disengages the arcing contact 16 and moves into proximity of the terminal 23 of the magnetic blowout 12, the magnetic field set up by the blowout coil 17 forces the arc on to the magnetic blowouts 11 and 12. As the turns near the lower ends of the blowouts are thus energized by the current flowing in the arc circuit, these turns serve to set up a

magnetic field transverse the path of the arc in the proper direction as to react upon the arc so as to cause the ends of the arc to move upwardly along the magnetic blowouts 11 and 12. As the successive turns of the winding forming each of the blowouts are thus successively connected in the arc circuit the actuating transverse component of flux falls in close proximity to the end of the arc. Also as more and more turns of the windings forming the blowouts 11 and 12 are connected in the arc circuit, the increased reactance serves to materially reduce the value of the current in the arc itself. Under the joint influence of the transverse magnetic fields and the increased reactance in the arc circuit, the arc is finally stretched and attenuated as indicated in dotted lines in Fig. 1 so that the arc itself is ruptured.

While I have illustrated and described the magnetic blowouts 11 and 12 as formed of a conductor wound in notches upon an insulating core, the winding may be formed of suitable shape and cast in concrete if desired with the overlapping portion of the successive turns of the winding exposed to form a composite arcing terminal. Furthermore, suitable renewable arcing contacts may be provided for the arcing portions of the successive turns of the winding if desired.

What I claim as new and desire to secure by Letters Patent of the United States is:

1. A magnetic arc blowout for a circuit interrupter comprising an elongated core having transverse slots in opposite sides thereof, and a winding having the successive turns located in said slots with the interconnecting portion of the winding on at least one side of the core disposed at an oblique angle to the axis of the core and exposed to form a composite arcing terminal along which the arc is driven by the leakage flux of the winding.

2. The method of breaking an electric circuit which consists in establishing an initial arc and forming a following preponderant magnetic field independent of the magnetic field of the arc at one side of the arc to move the arc for extension.

3. The method of breaking an electric circuit which consists in establishing an initial arc between diverging termini forming a gradually widening gap and forming a following preponderant magnetic field independent of the magnetic field of the arc at one side of the arc to move the arc along the gap.

4. The method of breaking an electric circuit which consists in establishing an initial arc and forming a following preponderant magnetic field at one side of the arc with a greater magnetic field strength adjacent to a terminal than at intermediate parts of the arc to move the arc for extension.

5. The method of breaking an electric circuit which consists in establishing an initial

arc and forming two magnetic fields with a preponderance at one side of the arc and with axes across the axis of the arc and adjacent to the termini of the arc.

5 6. The method of breaking an electric circuit which consists in establishing an initial arc and forming two magnetic fields with a preponderance at one side of the arc and with axes across the axis of the arc and adjacent to and outside of the termini of the arc.

10 7. The method of breaking an electric circuit which consists in establishing an initial arc and forming two magnetic fields with a preponderance at one side of the arc and with axes across the axis of the arc and with the same direction of flow between the termini.

15 8. The method of breaking an electric circuit which consists in establishing an initial arc and forming two magnetic fields with a preponderance at one side of the arc and with axes across the axis of the arc and in the direction of flow of the magnetic field of the arc at the side of the arc toward the preponderance of the side fields.

20 9. The method of breaking an electric circuit which consists in mechanically initially breaking the circuit to form an arc and forming a following preponderant magnetic field independent of the magnetic field of the arc at one side of the arc to move the arc so initially formed for extension.

25 10. The method of breaking an electric circuit which consists in establishing an initial arc between diverging termini and forming by coils along a terminus, an actuating field of greater intensity at the terminus of the arc adjacent to the coil than nearer the center of the arc whereby the terminal advance 30 of the arc may be proportioned to the advance of the central portions of the arc.

35 11. The method of breaking an electric circuit which consists in establishing an initial arc between diverging termini and forming by coils along each terminus an actuating field of greater intensity than at the center of the arc whereby the terminal advance of the arc may be proportioned to the advance of the central portions of the arc.

40 12. The method of breaking an electric circuit which consists in establishing an initial arc and forming a following magnetic field independent of the magnetic field of the arc at one side of the arc to move the arc for extension.

45 13. The method of breaking an electric circuit which consists in establishing an initial arc and forming a following magnetic field at one side of the arc with a greater magnetic field strength adjacent to a terminal than at intermediate parts of the arc to move the arc for extension.

50 14. In an electric circuit breaker, the combination of diverging arc-forming terminals; and means comprising a magnetic field form-

55 ing coil forming a preponderant magnetic field at one side of the arc along one of said terminals.

60 15. In an electric circuit breaker, the combination of diverging arc-forming terminals, 70 and means comprising a magnetic field forming coil forming a preponderant magnetic field at one side of the arc along both of said terminals.

65 16. In an electric circuit breaker, the combination of diverging arc-forming terminals; and means comprising a magnetic field forming preponderant magnetic fields at one side of the arc along said terminals with the same direction of flow of said fields between said 80 terminals.

70 17. In an electric circuit breaker, the combination of diverging arc-forming terminals; and means comprising a magnetic field forming coil forming preponderant magnetic fields 85 at one side of the arc along said terminals with the same direction of flow of said fields between the terminals and in the direction of the flow of the side of the field of the arc subjected to the terminal fields. 90

In witness whereof, I have hereunto set my hand this 9th day of July, 1926.

CERTIFICATE OF CORRECTION.

Patent No. 1,796,066.

Granted March 10, 1931, to

OLIVER C. TRAVER.

It is hereby certified that error appears in the printed specification of the above numbered patent requiring correction as follows: Page 3, line 78, claim 16, before the word "preponderant" insert the words coil forming; and that the said Letters Patent should be read with this correction therein that the same may conform to the record of the case in the Patent Office.

Signed and sealed this 14th day of April, A. D. 1931.

**M. J. Moore,
Acting Commissioner of Patents.**
